UNITED STATES PATENT OFFICE.

PIETRO VERGNANI, OF SOMERVILLE, MASSACHUSETTS.

MELTING-FURNACE.

1,121,957.

Specification of Letters Patent. Patented Dec. 22, 1914.

Application filed May 3, 1911. Serial No. 624,836.

To all whom it may concern:

Be it known that I, PIETRO VERGNANI, a citizen of the Kingdom of Italy and subject of Victor Emanuel III, and a resident of 5 Somerville, county of Middlesex, and State of Massachusetts, have invented an Improvement in Melting-Furnaces, of which the following description, in connection with the accompanying drawings, in a specification, like characters on the drawings representing like parts.

This invention relates to metal furnaces and pertains more particularly to a furnace for the fusion of metals and having various 15 features of improvement over those heretofore known in the art.

For illustration I have shown in the accompanying drawings one of the embodiments of which my invention is susceptible.

20 In the drawings: Figure 1 is a front elevation of my invention. Fig. 2 is a rear elevation of Fig. 1, with portions of the carriage and fire dome broken away. Fig. 3 is a section on line 3—3 of Fig. 2 looking in 25 the direction of the arrow. Fig. 4 is a section on line 4—4 of Fig. 2 looking in the direction of the arrow. Fig. 5 is an enlarged detail of the fire dome lifting drum. Fig. 6 is an enlarged section on line 6—6 of Fig. 30 3 looking in the direction of the arrow. Fig. 7 is an enlarged section on line 7—7 of Fig. 3 looking in the direction of the arrow. Fig. 8 is an enlarged section on line 8—8 of Fig. 3 looking in the direction of the arrow. Fig. 35 9 is an enlarged section on line 9—9 of Fig. 2 looking in the direction of the arrow. Fig. 10 is a section on line 10—10 of Fig. 2. Fig. 11 is a modified form of carriage.

It is understood herein that the terms 40 used are in the generic and descriptive sense and not as limitations as the latter will be defined within the proper scope of the claims.

Referring to Fig. 1 of the drawings, a pair 45 of vertical frames 10—10 are supported upon a carriage 11 mounted upon traction wheels 12—12 and 13—13. The trailer end of the carriage is provided with ears 14—14 integral therewith to receive the trunnions 50 15—15 of the wheels 13—13. The draft end of the carriage is provided with vertical extensions or hangers 16—16 to receive the vertical pivots 17—17 of the wheel forks 18—18 55 12—12. By this means the draft wheels 12—12 are constructed to turn about the

pivots 17—17 in order that the carriage may be turned or moved in the desired direction.

A drop handle 20 pivoted in the ears 21—21 on the carriage, is adapted to be 60 raised from the draft position and locked to the frame 10 when the furnace is in operation and when it is desired to move the carriage about the shop or foundry the said handle is lowered to the draft position and 65 the operator thereby moves the furnace where desired. Other means may be employed to accomplish the desired result when the furnace is of sufficient size and weight as to be beyond the strength of one or two 70 operators.

The furnace proper is located between the frames 10—10 and it may be of any desirable and proper shape or conformation. Herein I have illustrated the furnace body 25 as 75 slightly frusto-conical and having therein a heating chamber 26. This body is comparatively thin and may be a single casting or built up of steel plates and provided with a relatively thick lining of refractory or fire 80 resisting material 27.

At two diametrically opposite points on the furnace body I provide trunnions 28 and 29 that enter bearings 30 and 31 in the frames 10—10 in order that the furnace body 35 25 may be rotated between the said frames. A nut and check-nut on the trunnion 28, and the worm gear 32 on the trunnion 29, engage with the outside faces of the bearings 30 and 31 respectively to prevent springing and 90 warping of the frames 10—10. The worm gear 32 is locked to the trunnion 29 and is rotated by a worm 33 splined to a shaft 34 journaled in bearings 35 located on the frame 10, see Figs. 2 and 4. To rotate the 95 shaft 34 I provide any suitable mechanism or power motor depending upon the size and weight of the furnace. In the larger sizes of furnaces I will drive the shaft 34 by means of an electric motor while in the 100 smaller sizes I will provide hand power mechanism. Herein I have illustrated a bevel gear 37 splined to the shaft 34 and driven by the bevel gear 38 secured to the shaft 39 in the bearing 40 on the frame 10. 105 A hand wheel 41 is splined on the shaft 39 at the opposite end of the bearing 40.

By means of the above described mechanism, steady and careful pouring of the metal is accomplished as will be more fully 110 described hereinafter, but the reversal of this mechanism may be too slow in opera-

tion when it is desirable to return the furnace more quickly to the normal position to stop the flow of metal or to prevent an accident. To this end I provide mechanism 5 to unlock the worm gear 32 from the trunnion 29 so that the furnace can be restored to the normal position by quick return means. Herein for convenience I have illustrated the worm gear 32 as normally clutched at 45 to the sliding sleeve 46 feathered at 47 to the trunnion 29. A circumferential groove 48 on said sliding sleeve is designed to receive the rollers 49 on the swinging end of a forked hand lever 50 pivoted at 51 to bearing 40 on the frame 10; see Figs. 2 and 4. By moving the handle end of the hand lever 50 in the direction of the arrow in Fig. 2, the free end thereof will slide the sleeve 46 axially of the trunnion 29 thereby disengaging the teeth on said sleeve at 45 from the teeth on the worm gear 32 and the trunnion will be free to rotate while the worm gear will be held stationary by the worm 33. Assuming 25 that at the time the above operation takes place the furnace is in the dotted line position illustrated in Fig. 3 it can be moved to the full line position by the operator who grasps the handle 53 and pulls the same 30 downward. This handle 53 may be secured to the furnace in any suitable manner, preferably however it may be connected with or form a part of a safety device to prevent damage or injury if the furnace should 35 continue its movement in the pouring direction or to prevent its swinging back in the reverse direction and to the normal position too suddenly when there is any considerable weight of metal left in the furnace at the 40 time and the operator fails to grasp the handle 53 at the unclutching of the worm gear 32 from the trunnion. It is apparent that any suitable limiting means designed to act on the furnace body and limit the 45 movement thereof, will accomplish the above mentioned result. I have illustrated a simple means or safety device composed of a segment 54 integral with the handle 53, and attached to the furnace body 25 about the 50 trunnion 29. The said segment is adjacent to the frame 10, and through the former is a plurality of staggered holes 55 to receive a removable stop pin 56 projecting in the path of the stop 57 on the frame. By placing the stop pin 56 in any one of the holes 55 the furnace will be limited in the pouring movement about the axis thereof. From the point 60 on said segment 54 the segment and handle 53 are free from attachment or contact 60 with the furnace body in every way and is bent toward the frame 10 thereby forming a spring member bearing against the said frame with increasing pressure as the furnace moves to the normal position. In 65 order that the furnace may not swing by

the normal position while it is so moving against the tension of the spring segment 54, I provide the said segment with holes 61 adapted to receive a removable stop pin 62 that projects in the path of a stop 63 on 70 the frame 10. By this means the downward or return movement of the furnace is checked and must finally stop when the stop pin 62 contacts with the stop 63.

In carrying out my invention, I in this 75 embodiment thereof provide a fuel burner with means to feed and regulate fuel thereto and further means in combination with said fuel burner to regulate and vary the combustion of the fuel ejected therefrom. 80 The said burner may be of any desired type employed for burning oils, and it may be located at any desired and proper point relative to the furnace body, most necessary to produce the best results. I may 85 employ one burner or I may provide a plurality of burners of a single type or they may be of different types in order to gain the most desirable result or the highest efficiency depending upon the nature and kind 90 of furnace employed. In the present embodiment of the invention, I have illustrated a single burner 65 depending from the bottom of the furnace body 25.

To the construction and arrangement of 95 the burner illustrated and described, I am not limited thereto except as pointed out in the appended claims, as any efficient oil burner will produce good results. However certain new results are produced by the 100 burner illustrated that makes it specially applicable to this type of furnace and gives more efficient results as will be described hereinafter.

The burner 65 is secured to the furnace 105 body 25 in any suitable manner or it may be integral therewith and is provided with a central bore or combustion chamber 66 having a lining 67 of refractory or fire resisting material. The combustion chamber 66 communicates with the heating chamber 26 at the bottom thereof and the fire therefrom is directed upward and throughout the said heating chamber by means of the flaring neck 68. The end of the said 110 combustion chamber 66 opposite the junction thereof with the furnace is provided with a nozzle or fuel jet 70 to which the oil is fed and vaporized. Owing to the intense heat generated I preferably employ 115 refractory material for the nozzle 70 and secure the same to a base 71 supported by links 72 pivoted at 73 to ears 74 on the outside of the burner 65. To enable the nozzle 70 to be readily removed for renewal or repairs, I preferably slot the ends 75 of the base 71 passing therewith the rounded lower part of the links 72—72 and pivot on the ends thereof bifurcated eccentric cams 76—76 adapted to engage the base 71 on 120 125 130

either side of slots to clamp said base to the squared ends 77—77 of the links as illustrated in Fig. 2. When said cams 76—76 are moved in the opposite direction to that illustrated in Fig. 2, the base is unclamped from the links 72—72. When this is done the links may be turned about the pivots 73—73 to free the base therefrom and the said base may be withdrawn from the combustion chamber 66. Thus the base and combustion chamber are readily accessible for all purposes and the assembling can be done in a moment's time.

Fuel is supplied to the nozzle 70 in any suitable manner, preferably however it is admitted to said nozzle through separate conduits 80 and 81 leading from the bottom of the base 71 to the top thereof and into chambers 83 and 84 respectively. The chamber 83 is substantially semi-circumferential and supplies a plurality of vertical passages 85 emptying into the trough shaped portion 86 located just below the top of the nozzle. This trough permits of use as a pilot light and also to volatilize the fuel within the nozzle chambers 83 and 84 and serves when desired the purpose of enriching the hydrocarbon mixture emitted from the main jets in the nozzle. The chamber 84 supplied from the conduit 81, is radial and does not communicate with the chamber 83. Arising centrally of the nozzle 70 and communicating with the chamber 84 are a plurality of jets 87 through which the main body of hydrocarbon is projected into the combustion chamber 66 and there burned. A circumferential trough 88 below the trough 86 is for the purpose of catching and burning therein any overflow of fuel from the trough 86 and jets 87. In order to obtain a complete combustion of the hydrocarbon, more or less oxygen is admitted to the combustion chamber 66 preferably in varying quantities and at different heights relative to the burner 65 as the different conditions of fuel and the atmosphere vary. For convenience of illustrating the manner in which this may be accomplished, the body of the burner 65 terminates a short distance above the nozzle 70 and there is provided means for admitting between said burner and nozzle, oxygen in greater or less volume at varying heights. Removably secured to the extreme end of the burner 65 and holding the same thereto by means of screws 90 beneath a flange 91, is a tubular member 93 having therethrough a plurality of rectangular openings 94 for the admission of oxygen to the combustion chamber 66. The entering oxygen and the volatilized fuel emitted from the jets 87 commingle and when properly proportioned forms a mixture that is easily and highly combustible. The proper proportions cannot be assured at all times if the different elements were ad-

mitted in the same quantities under different atmospheric conditions and if the fuel varies in calories. To vary the amount of oxygen and also admit the same at varying heights through the rectangular openings 94, I preferably provide a vertically movable tubular damper member 101 having therethrough slots 102 that register with the openings 94 in the tubular member 93. When said tubular damper 101 is moved axially in either direction the point of admission of the oxygen is raised or lowered relative to the nozzle 70 depending upon the direction of the movement. This is due to the fact that the slots 102 are shorter than the openings 94. When the movement is continuously in one direction, as for example when the tubular damper 101 is moved upward, the blank portion 103 on said damper will if moved far enough entirely close the openings 94 and the same effect is obtained in the reverse direction by the blank portion 104 approaching the edge of the nozzle 70 where the said edge limits the lower point of admission of oxygen. In order to accomplish the movement of the damper in an axial manner, I support the same on trunnions 105—105 passing through the lower ends of links 106—106 suspended from a bifurcated hand lever 107 extending circumferentially of the body of the burner 65. The hand lever 107 is pivoted at 108 to an ear 109 on said burner and is provided with and thereby held in any desired position by a spring pressed pawl 110 engaging notches on a segment 111 secured in any suitable manner to the burner 65 or to the furnace body 25. The use of a mechanism of this character enables the damper 101 to be locked in the adjusted position.

Interposed between the fuel reservoir 115 shown diagrammatically in Fig. 1, and the base 71 is the fuel supply and control means with mechanism therefor for quickly detaching the same from the base 71. The fuel reservoir 115 may or may not be attached to the frame 10. When not attached a single reservoir may supply one or more furnaces with fuel and be detachable from all of said furnaces.

I will proceed first to describe the fuel supply and control means and then I will describe the manner of attaching the same to the base 71.

The fuel supply means consists of fuel pipes 116 and 117 leading from the conduits 80 and 81 respectively, to the fuel valves 118 and 119 respectively supported by a protecting hood 120 secured in any suitable manner to the furnace body 25. An air pipe 121 connected at 122 with the fuel pipe 117 leads to the air valve 123 also supported by the hood 120. The said hood 120 is provided for the purpose of protecting the valves 118, 119, and 123 from the action of

the heat radiating from a fire dome, to be hereinafter described, when said fire dome is raised and the furnace is in the pouring position and the said valves are beneath said dome as illustrated in dotted lines in Fig. 3.

In order to provide a means to determine the amount of opening of the valves just referred to, I preferably employ pointers 125 on the handles of the valves to indicate 10 on their respective scales on a graduated plate 126 secured to the hood 120, the relative degree of opening for each valve.

A branch coupling 128 connects the valves 118 and 119 to a common fuel supply pipe 129 leading to the fuel reservoir 115. This supply pipe 129 is detachable from the branch coupling 128 by means of any connection or coupling of suitable construction requiring a relative partial turn to connect or disconnect the same.

The manner in which the fuel is forced from the tank 115 to the pipe 129 is common to many fuel feeding devices and may consist of a pump located along the pipe 129 or compressed air may be forced into the tank or reservoir 115 at the top thereof by means of an air compressor shown diagrammatically in Fig. 1.

The air valve 123 is detachable from an 30 air supply pipe 135 by means of a quarter turn coupling 136 similar in construction to the coupling 130. This air pipe is also connected to an air compressor 136'. By this means I can force any quantity of air directly into the fuel and heat the same at the same time that the fuel is volatilized.

The manner in which the fuel pipes 116 and 117 are attached to the base 71 preferably require a coupling means that is readily 40 and quickly attached without going to the time and trouble of unscrewing a coupling or coupling nut or the like with the attendant troubles of damaged threads and lost bolts every time the parts are detached.

Detaching these parts will occur frequently as the fire proof linings will require repairs and renewal. I have illustrated herein a means for quickly removing the said pipes 116 and 117 consisting of tapered sleeves 140 50 on said pipes fitting into similarly tapered seats 141 in the conduits 80 and 81. Rotatable collars 142 having thereon at diametrically opposite points a pair of tapered lugs 143 are adapted to engage with a pair of oppositely tapered lugs 144 integral with the base 71 and located at diametrically opposite points about each of the conduits 80 and 81. See Figs. 3 and 8. By this means the sleeves 140 will be forced tightly to the

60 seats 141 in the respective conduits when the coacting lugs are forced together. Handles 145 integral with the rotatable collars 142 provide a ready means for turning said collars in either direction to cause the lugs 65 to engage or disengage.

Auxiliary twyers 150 are spaced about the body of the furnace and are adapted to furnish further oxygen above the burner 65 to assist in a more complete combustion of the fuel about the point of the greatest mass of 70 metal within the furnace. Slides 151 cover the outer ends of these twyers and are adapted to slide in guides 152 so that as circumstances demand, more or less air can be admitted at this point to increase the rate of 75 combustion within the furnace body.

Within the heating chamber 26 I provide any suitable refractory or fire resisting container for the reception of the metals to be melted. This container may be integral 80 with the lining 27 and may be of any desired conformation so long as sufficient space surrounding the same is provided for the action of the heating agent. Preferably however for convenience and for the ease with 85 which the same can be renewed I provide or utilize standard size crucibles 155 of smaller diameter than the diameter of said heating chamber 26 and set and space the crucible concentrically within the fusion chamber.

A plurality of radial blocks 156 arise from the bottom of the fusion chamber 26 at the point where the burner 65 joins the former. A disk or biscuit 157 is adapted to set within notches 158 at the top of the blocks 156. 95 This biscuit 157 serves the double purpose of supporting the crucible 155 and prevents erosion thereof at the bottom by the hot gases impinging thereagainst.

One or more fire resisting wedges 160 placed between the crucible 155 and the wall of the heating chamber 26 at the top thereof are adapted to hold the said crucible in place centrally of the heating chamber and keep the pouring spout or lip 161 on the crucible 100 against the pouring lip 162 cut through the furnace body or the lining 27. By this means the crucible 155 is securely wedged in place and cannot fall out when the furnace body is in an inverted or partially inverted 105 position during pouring.

An upturned annular flange 163 surrounding the inner edge of the lining 27 of the fusion chamber 26 is adapted to be received within an annular depression 164 in the edge 115 of a fire resisting lining 165 within a substantially semi-spherical fire arch or fire dome 166. This method of construction effectually closes the joint between the two members last mentioned by directing the 120 burning gases past the outer joint between the same.

The fire dome 166 is adapted to rest upon the top edge of the furnace body 25 to inclose the heating chamber 26 and concentrate the heating agent all about the crucible 155 while the metal is being melted. When the metal has reached the molten stage and is at the proper pouring temperature, I preferably raise the fire dome 130

166 from the furnace body 25 so that said body may be swung about the trunnions 28 and 29 to pour the metal direct from the crucible 155 without removing the same from the heating chamber 26. For the purpose of raising said fire dome 166, I provide the same with diametrically opposed ears 167 to which are secured lifting chains 168 passing upward and over a pair of pulleys 169 between a pair of ears 170 on a cross frame 171 secured to the frames 10-10. The upper ends of the chains 168 are secured to ears 172 on a forked lifting lever 173 pivoted at 174 to ears 175 on the cross frame 171. This lifting lever 173 is provided with an adjustable counter-weight bar 176 clamped within a yoke on the former by means of a set-screw 177. A counter-weight 178 is movable along said bar 176 and is secured thereto by means of a set-screw 179. To a ring 180 integral with the counter-weight bar 176 is secured a lifting cable 181 the opposite end thereof passing about a flanged winding drum 182 on a shaft 183 mounted in bearings 184 on the frame 10. A hand wheel 185 on the shaft 183 enables the operator to turn the winding drum 182 to wind up the cable 181 thereby pulling down the counter-weight 178 and bar 176 thus lifting the forked lifting lever 173 to pull up the fire dome 166. A ratchet 186 on the edge of one flange on the winding drum 182, engages with a drop pawl 187 thus to prevent unwinding of the cable 181 from the drum 182 when the fire dome is in the raised position. Preferably the fire dome 166 is arranged to be guided in a vertical manner by means of diametrically opposed grooved guides 189 engaging with the slides 190 on the frames 10-10. The guides 189 are so constructed and arranged that they may be unclamped and moved radially inward toward the center of the fire dome 166 and freed from engagement with the slides 190. For this purpose the said guides are provided with shanks 191 adapted to be received within bushings 192 integral with the fire dome 166. Clamp screws 193 secure the shanks 191 in the desired position within the bushings 192. This construction permits the fire dome 166 to be detached from the slides 190 and thereby removed from between the frames 10-10 when it is necessary to renew or to repair the lining 165.

In order to properly handle the fire dome 166 and entirely remove the same from between the frames 10-10 I preferably provide a swinging crane 195 pivoted at 196 to ears 197 on the frame 10 opposite to that frame 10 carrying the dome lifting drum 182. The boom 198 of the crane 195 is provided with journals 199 within which is a rotatable shaft 200 carrying a winding drum 201 provided with a ratchet 202 engaging a pawl 203. A relatively large hand wheel 204 is securely keyed to the shaft 200 to turn said shaft and drum 201. A pair of lifting chains 205-205 are secured to the winding drum 201 at diametrically opposite points in order that they will be wound up simultaneously when the said drum is rotated. These chains 205 pass about idlers 206 and over pulleys 207 depending therefrom. The lower ends of the said chains are provided with relatively thin and deep seated hooks 208 adapted to hook beneath the shanks 191 on the guides 189 thereby to lift the fire dome 166.

An opening 210 near the top of the fire dome 166 is closed with a removable block 211 adapted to be withdrawn from said opening when it is necessary to inspect the contents of the crucible 155 and to permit of testing the same with a pyrometer or the like.

I provide herein a combustion flue 215 at the top of the dome 166 to carry off the hot gases and products of combustion arising from the fusion chamber 26. The flue 215 is lined with fire resisting material throughout. Bolts 217 secure the flue 215 to the flange 218 on the fire dome 166 in order that the said bolts may be withdrawn to permit removal of the said flue when it is necessary to reline either the flue or dome. The flue 215 projects within and slides vertically in a short stack 220 secured to the cross frame 171 bolted to the frames 10-10. The stack 220 is provided with a refractory lining 221 to prevent erosion thereof by the hot gases arising from the combustion chamber 26.

A modified form of my carriage 11 is illustrated in Fig. 11. In this embodiment the carriage 11 has pivoted thereon at 224 a rotatable sub-base 225 on which is mounted the frames 10-10. This construction enables the entire furnace to be rotated about the pivot 224 thus enabling two lines of flasks or molds to be served when the traveling space between them is too narrow to permit turning the entire carriage within the restricted space.

The operation of my invention is as follows: The crucible 155 is placed in position within the fusion chamber 26 and wedged therein by the wedges 160. I have assumed that at this time the fire dome 166 is in the raised position shown in dotted lines in Fig. 3 and the furnace body 25 is in the full line position shown in the same figure. The crucible is now loaded with the metal it is desired to melt and the fire dome 166 is permitted to descend in the proper position on top of the furnace body 25. The heating chamber is now entirely inclosed to concentrate the fire about the crucible 155. The furnace is now in position beneath a

hood or flue 230 see Fig. 1 communicating with the atmosphere without the building. The fuel coupling 130 is now connected to the branch coupling 128 thereby providing 5 a supply conduit leading from the fuel reservoir 115 through the common supply pipe 129 the said branch coupling 128, the valves 118 and 119 and their respective fuel pipes 116 and 117 to the conduits 80 and 81 respectively within the burner 65. The quarter turn coupling 136 is also connected joining the air compressor 137 with its supply pipe 135 to the air valve 123 and the air pipe 121. The valve 118 is now opened to 10 permit fuel to flow therethrough to the pipe 116 through the conduit 80 to the chamber 83. From the chamber 83 the fuel is forced upward through the vertical passages 85 and spreads about the trough 86. This fuel 15 is ignited and allowed to burn in the said trough. When the trough 86 has been heated to the proper temperature to volatilize the fuel admitted to the chamber 84 the valve 119 is opened to permit fuel to flow to said 20 chamber. During this time the rectangular openings 94 have been open to admit sufficient oxygen to maintain the proper combustion of the fuel burned in the trough 86. When the fuel admitted to the chamber 84 25 has forced its way through the jets 87 and has become ignited the air valve 123 is opened very slightly to admit a quantity of air to the main body of fuel within the chamber 84 there to commingle with said fuel and force the same upward toward the 30 combustion chamber 26. This admits of an initial mixture of oxygen and fuel. The damper 101 is now moved up or down to change the point of admission of oxygen 35 and give a greater or less passage through the openings 94. The auxiliary twyers 150 are opened to the necessary extent to promote more intense combustion about the main body of metal. When the main jets 40 45 87 are in proper working order the pilot light may be turned down to burn very low to provide just enough flame to ignite the main jet in case it should be blown out by the force of the air from the pipe 121 or the 50 entering oxygen. When the lining 67 has become highly heated this is not so likely to happen as the red hot walls thereof will tend to keep the main jet lighted. When the metal has reached the proper pouring 55 60 65 temperature the valves 118, 119, and 123 are closed and the couplings 130 and 136 are disconnected from their respective parts and the furnace is now ready to be moved to the flask or mold to be filled with the metal. The drop handle 20 is lowered and grasped by the operator who pulls the furnace in the desired direction and alongside of the mold. The operator now grasps the hand wheel 185 and turns the same to raise the 65 fire dome by means of the mechanism here-

inbefore described. When the dome 166 is in the position illustrated in Fig. 3, the operator moves the handle lever 50 in the reverse direction of the arrow in Fig. 2 thereby locking the worm gear 32 to the trunnion 70 75 29. When this is done the operator grasps the hand wheel 41 and rotates it in the proper direction to revolve the furnace about its trunnions to pour the metal from the crucible without removing the same from the furnace. The metal runs out by the lip 161 in a thin stream and enters the gate of the flask until the flask is full. When it is noticed that the flask is about full the hand lever is moved in the direction of the arrow 80 Fig. 2 disengaging the teeth on the sleeve from the teeth on the worm gear 32 when the furnace will swing back to the upright position. The furnace is now ready to be run to the next flask and the above operations repeated. When the furnace is emptied of the metal it is ready to be recharged and the above operations repeated. 85 90

I have described herein one embodiment of my invention; but it is to be understood that the latter is not essentially limited to the specific details of construction and organization of said embodiment, since the same may be varied without departing from the proper scope of the claims. 95

Claims:

1. In a furnace, an axially movable furnace body, as described, a fusion chamber therein, a relatively movable fire dome for said chamber, a frame to support said furnace body, a carriage for said frame, and vertical pivotal means interposed between said frame and said carriage to permit relative rotation between said frame and carriage. 100 105
2. In a furnace, a carriage, traction wheels therefor, a frame on said carriage including vertical pivotal means to permit relative rotation between said carriage and frame, a furnace body including a fusion chamber, trunnions on said furnace body to engage bearings in said frame, bearings in said frame to support said furnace body, detachable rotating mechanism secured to said frame and adapted to lock to one of said trunnions to rotate the furnace body in either direction, means to supply heat to said fusion chamber, means for supplying oxygen to said heating means in varying quantities, a fire dome for said furnace body, mechanism on said frame to move said fire dome relative to said furnace body, a counter-weight on said last mentioned mechanism, and guides on said fire dome to engage said frame. 110 115 120 125
3. In a furnace, a carriage, traction wheels therefor, vertical pivotal mechanism on said carriage, a frame including pivotal means to coact with the pivotal mechanism on said carriage, bearings in said frame, 130

vertical slides on said frame, a furnace body including a fusion chamber and trunnions to engage said bearings, mechanism on said frame adapted to engage with said trunnions to rotate the furnace body in either direction, means to supply and control liquid fuel to said fusion chamber, a fire dome for said fusion chamber, guides on said fire dome adapted to engage the vertical slides 10 on said frame, and mechanism on said frame to engage said fire dome to move the same along said slides.

4. In a furnace, a portable carriage and frame, a furnace body pivoted on said frame, a fusion chamber in said furnace 15

body, a relatively movable fire dome for said fusion chamber, means on said fire dome to engage said frame to be guided thereby, mechanism to engage said fire dome to impart movement thereto relative to said 20 fusion chamber, and means adapted to engage said fire dome to remove the same from moving relation with said fusion chamber.

In testimony whereof, I have signed my name to this specification, in the presence 25 of two subscribing witnesses.

PIETRO VERGNANI.

Witnesses:

GEORGE M. CLOUGH,

EDWIN T. LUCE.
